UNITED STATES PATENT OFFICE

152,953

DESIGN FOR AN ELECTRIC BROILER

Morris A. Feinstein, Chicago, Ill.

Application October 30, 1946, Serial No. 134,380

Term of patent 14 years

(Cl. D81—10)

To all whom it may concern:

Be it known that I, Morris A. Feinstein, a citizen of the United States, residing at Chicago, in the county of Cook and State of Illinois, have invented a new, original, and ornamental Design for an Electric Broiler, of which the following is a specification, reference being had to the accompanying drawing, forming part thereof.

Fig. 1 is a top plan view of an electric broiler showing my new design;

Fig. 2 is a front elevation; and

Fig. 3 is a fragmentary perspective view of one end.

The dominant features of the design reside in the portions shown in full lines.

I claim:

The ornamental design for an electric broiler, as shown and described.

MORRIS A. FEINSTEIN.
